UNITED STATES PATENT OFFICE.

RICHARD BOLLERMANN, OF NEW YORK, N. Y.

MOUSE-PROOF PIANO-PEDAL.

1,086,988.

Specification of Letters Patent. Patented Feb. 10, 1914.

Application filed August 8, 1913. Serial No. 783,696.

To all whom it may concern:

Be it known that I, RICHARD BOLLERMANN, a citizen of the United States, and a resident of the city of New York, borough of the Bronx, in the county and State of New York, have invented a new and Improved Mouse-Proof Piano-Pedal, of which the following is a full, clear, and exact description.

10 This invention relates to the construction of pianos and has particular reference to the construction of means for simply and effectively excluding mice from the interior of the piano.

15 Among the objects, therefore, of this invention is to provide a means for use in connection with a piano pedal which will automatically close the opening ordinarily left by the pedal when in its normal elevated position.

20 A further object of the invention is to provide a means of the character set forth which is practically invisible while the piano is in ordinary use and yet which 25 closes the passageway along the pedal by means exterior to the inside of the pedal mechanism whereby mice are prevented from entering and building nests within the piano as sometimes happens even though 30 the piano on the interior is equipped with a casing to prevent the mice from having access to the other parts of the mechanism.

The foregoing and other objects of the invention will hereinafter be more fully described and claimed and illustrated in the drawings forming a part of this specification in which like characters of reference indicate corresponding parts in both the views, and in which—

40 Figure 1 is a vertical section of a piano, indicating a pedal in side elevation in normal position, the section being on the line 1—1 of Fig. 2; and Fig. 2 is a plan view of the same, parts being in section on the line 2—2 of Fig. 1.

At 10 I show a conventional form of piano pedal having a shank 11 pivoted on a horizontal pivot at 12 and adapted to have connected in any one or more of a 50 series of holes 13 tone modifying devices (not shown). The pedal is supported upon a bracket 14 within the piano casing indicated at the corner between the front 15 and the floor or bottom 16. The front 15 is provided with the usual opening 17 through 55 which the pedal extends and in which it

oscillates on the pivot 12. The means for maintaining the pedal in its normal position do not form any part of this invention and hence are not illustrated. Said opening also is preferably lined with felt, as shown at 18, to deaden the noise which would be incidental to the movements of the pedal.

As indicated at 19 there is usually sufficient space between the pedal shank and the bottom of the casing, to provide for the movements of the pedal, to enable mice to pass freely into the piano through such space, and much damage oftentimes is done 60 by the mice for this reason. I am aware that it has been proposed heretofore to apply gates or slides to the pedals on the outside of the piano front for the purpose of excluding mice, but such devices are 65 objectionable because they mar the appearance of the instrument. I provide, therefore, an automatically operating gate or barrier 20 in the form of a coil spring, the same being located between the front part 80 of the pedal shank 11 and the floor 16. This gate is made preferably of spring metal wire of a very small gage or caliber, and has a resiliency sufficient for the purpose of extending itself so as to fill the space when 85 the pedal is in normal position, as shown in Fig. 1, but has insufficient strength to materially affect the depression of the pedal or its return to normal position. The barrier coil may be made of any suitable diameter 90 so as to completely fill the space, but preferably it is slightly larger than the normal space in width, and for this reason the piano front 15 is provided with vertical cylindrical oppositely arranged concavities, as 95 shown in Fig. 2, and these concavities serve to prevent any possible displacement of the barrier and yet provide for its proper vertical movements. It will thus be seen that I provide an automatically operating barrier 100 located within the piano front and between the pedal pivot and the front face of the casing front, and which will effectively exclude mice from the casing.

Having thus described my invention, I 105 claim as new and desire to secure by Letters Patent:—

1. The combination with a piano casing including a front, a bottom and a pedal pivoted in the casing, of a barrier to exclude 110 mice from the interior of the casing, said barrier being located within the piano front

and between said bottom and the pedal, said piano front having an opening through which the pedal extends and operates, and said barrier being in the form of a coil spring and substantially closing said opening below the pedal.

2. The combination with a piano casing including a front having an opening therethrough and a bottom, of a pedal extending through said opening and pivoted within the casing, said piano front opening having oppositely arranged vertical concavities, and

a flexible barrier located between the pedal and the casing floor and between said concavities, said barrier substantially filling the 15 opening between the pedal and the floor in all positions of the pedal.

In testimony whereof I have signed my name to this specification in the presence of two subscribing witnesses.

RICHARD BOLLMANN.
